UNITED STATES PATENT OFFICE.

WILLIAM HORNICH, JR., OF NEWARK, NEW JERSEY.

DESIGN FOR A BADGE-BAR.

SPECIFICATION forming part of Design No. 32,941, dated July 17, 1900.

Application filed April 27, 1900. Serial No. 14,636. Term of patent 7 years.

To all whom it may concern:

Be it known that I, WILLIAM HORNICH, Jr., a citizen of the United States, residing at Newark, in the county of Essex and State of New Jersey, have invented and produced a new and original design for a Badge-Bar; and I do hereby declare the following to be a full, clear, and exact description of the invention, such as will enable others skilled in the art to o which it appertains to make and use the same, reference being had to the accompanying drawings, and to letters of reference marked thereon, which form a part of this specification.

5 Figure 1 is a face view of a badge-bar of my new design, and Fig. 2 is a section of the same on line x.

As shown in the drawings, the leading or material feature of my design consists in a badge-bar of oval or elliptical shape, having a smooth plain surface and regular or entire edges devoid of scallops or such projecting

members, said edges being rearwardly rounded and presenting a smooth plain margin continuous with the said surface and devoid ²⁵ of beads or frame-like ornamental configurations.

In the drawings, a indicates a badge-bar of my new design. The face of the bar is smooth and plain to receive inscriptions or ³⁰ the like and is slightly convex, as shown in Fig. 2, with its margins curved more sharply backward to form smooth round edges d.

What I claim as new is—

The design for a badge-bar as herein shown ³⁵ and described.

In testimony that I claim the foregoing I have hereunto set my hand this 23d day of April, 1900.

WILLIAM HORNICH, JR.
